UNITED STATES PATENT OFFICE.

OTTO EGON BORK, OF COPENHAGEN, DENMARK.

PENCIL SHARPENER.

Application filed August 8, 1925. Serial No. 49,012.

To all whom it may concern:

Be it known that I, OTTO EGON BORK, a subject of the King of Denmark, residing at Copenhagen, Tagensvej 50, Denmark, have invented certain new and useful Improvements in Pencil Sharpeners (for which I have filed an application in Denmark, May 28, 1924), and of which the following is a specification.

10 This invention relates to a pencil sharpener of the type in which the wood and the lead of the pencil may be dealt with separately.

The hitherto known pencil sharpeners of 15 said type comprise a metal or other body having two conical bores with oppositely arranged seatings for two cutters or knives projecting each with a sharp edge in one of said bores.

20 It is a well known fact, that during the use the knife edge adapted to sharpen the lead or graphite will soon be dull, due to the relatively large hardness of the graphite, and in fact it is quite impossible to 25 procure a sharp steel edge which will not be dull in the course of very short time, when cutting in graphite.

The purpose of the present invention is to overcome the said drawback and the object of the invention is to form the knife or cutter, adapted to sharpen the lead or graphite, as a steel-plate, the edges of 30 which are not sharpened, but are either plane or hollow so that the edge in question would sharpen the graphite by scraping action instead of by cutting action.

If the said steel plate, adapted to sharpen the graphite, is square it will have eight edges—four along each side face—which in 35 succession can be employed for the scraping purpose. Instead of being quadrangular the steel plate may have another polygonal shape preferably of such regular form, that any desired edge of the said plate may 45 be arranged to project into the conical bore in question and thereby serve the scraping purpose.

On the drawing show:

Figure 1 an embodiment of a pencil 50 sharpener according to the invention,

Figures 2 and 3 two different side views of the pencil sharpener according to Figure 1,

Figure 4 an end view of the pencil 55 sharpener, and

Figures 5 and 6 a longitudinal section and a cross-section, respectively, of the pencil sharpener according to Figure 1.

Figure 7 is a longitudinal sectional view of the pencil sharpener in operation, and 60

Figure 8 is a plan view of the pencil sharpener.

1 is a metal or other body having two conical bores 2 and 3. The body 1 is in well known manner cut away along the bore 65 2 in order to form a seating for a cutter or knife 5, the sharp edge 6 of which projects into the bore 2 and is adapted to remove the wood from a pencil, the end of which is brought into the bore 2 and rotated therein. The knife or cutter 5 has a longitudinal slit 8 adapted to receive a screw 4 by means of which the cutter 5 is 70 adjustably fixed to the body 1.

The bore 2 terminates in a cylindrical 75 bore 7, having a relatively large diameter, i. e., diameter, which allows the graphite or lead, or crayon of pencils of the thicknesses in question to move freely in the bore 7. When unscrewing the screw 4 the 80 cutter 5 may be moved longitudinally and thus adjusted to remove the wood of pencils of different thicknesses without scraping or cutting the graphite or lead or crayon of the pencil in question. In order 85 to avoid that the corner 20 of the cutter 5 will cut or scrape the graphite or crayon, the said corner may be convex instead of being concave as shown.

The graphite or crayon of the pencil is 90 subsequently sharpened by insertion of the end of the pencil, from which the wood has been removed by means of the cutter 5, into the conical bore 3, which similarly to the bore 2 terminates into a short cylindrical bore 9, which, however, has a considerably smaller diameter than the bore 7. The body 1 has near the bore 9 a recess 19, Figures 3 and 6, which communicates with the bore 3 or 9 and forms a 95 seating for a cutter or scraper 10, which in the embodiment shown is a quadrangular plate, the circumscribing faces of which are either flat and perpendicular to the side faces of the plate, or hollow so that the edges of the plate will not form knife edges, but scraping edges. 100

The plate 10 is preferably arranged at a suitable angle relatively to the side face of the body 1, so that one of the edges of the 110

plate 10, i. e., the edge 11 in Figures 5 and 6 is located in the bore 3 or 9. The said edge 11 would effect a scraping action on the graphite or crayon of the pencil, when 5 the end of the latter is inserted in the bore 3 and rotated.

The plate or scraper 10 is fixed to the body 1 by means of a screw 13. The plate 10 may be turned about the axis of this 10 screw, when the latter is unscrewed, and thus anyone of the edges of the plate 10 may be caused to project into the bore 3 or 9. If the screw 13 is removed, the plate 10 may be turned over, so that the under- 15 side of the plate 10 in Figure 6 may be turned upwardly and the edge along same applied for the scraping effect. Thus a quadrangular plate 10 will have eight applicable scraping edges.

20 Instead of being quadrangular the plate 10 may have any other polygonal shape and will then present a correspondingly larger or smaller number of scraping edges.

The shape of the body 1 and the positions of the bores 2 and 3 relatively to one another do not form parts of the invention, but may be varied in any desired manner.

Thus the two bores 2 and 3 may be arranged in prolongation of one another to form together a single bore, as shown in Figures 7 and 8. The scraper 10 and the cutter 5 are, by this embodiment of the invention, arranged to project both in said single bore 35 in such a manner that the scrapers 10 will effect a scraping action on the lead 30 of the pencil 40 simultaneously with the removal of the wood from the adjacent part of the pencil by means of the cutter 5.

40 Having now particularly described and ascertained the nature of my said invention and in what manner the same is to be performed, I declare that what I claim is:—

1. A pencil sharpener, comprising a body 45 part with a conical bore therein, and a cut-away part forming a longitudinal opening into the conical bore, a knife-edge cutter mounted in said cut-away part and having its cutting edge projecting longitudinally into the conical bore, a scraper mounted on

the body part and adapted to sharpen the lead of the pencil only, the said scraper consisting of a polygonal plate arranged to be turned in the plane of its support on the body part in order that any one of its circumferential edges may be brought in position to project into the conical bore in the body part to exert a scraping action on the lead of the pencil or crayon. 55

2. A pencil sharpener, comprising a body 60 part with a conical bore therein, and a cut-away part forming a longitudinal opening into the conical bore, a knife-edge cutter mounted in said cut-away part and having its cutting edge projecting longitudinally into the conical bore, and a scraper mounted on the body part and adapted to sharpen the lead of the pencil only, the said scraper consisting of a polygonal plate with rectangular scraping edges, the plate being rotatably mounted on the body part and capable of being turned in the plane of its support in order that any one of its circumferential edges may be brought in position to project into the conical bore in the body 75 part and to exert a scraping action on the lead of the pencil or crayon.

3. A pencil sharpener comprising a body part with two conical recesses therein, a cut-away part forming a longitudinal opening 80 into one of the conical recesses, a knife-edge cutter mounted in said cut-away part, and arranged to project with its cutting edge longitudinally into the recess, and a scraper mounted upon the body part and adjacent one end of the second conical recess, the scraper being adapted to sharpen the lead of the pencil only, the said scraper consisting of a polygonal plate with rectangular scraping edges, the plate being mounted on the body part and rotatably mounted to be turned in the plane of its support in order that any one of its circumferential edges may be brought in position to project into the second conical recess to exert a scraping action on the lead of the pencil or crayon. 85 90 95

In testimony whereof he hereunto affixes his signature.

OTTO EGON BORK.
